PRONG AND SCREW PLUG

Harley J. Schoon, Canton, Ill.

Application September 17, 1947, Serial No. 774,581

6 Claims. (Cl. 173—361)

1

This invention relates to a prong and screw plug, and has for one of its objects the production of a simple and efficient electrical contact plug wherein the screw plug may be conveniently moved to an extended position and may be freely rotated when in this position for threading into a screw socket.

A further object of this invention is the production of a simple and efficient prong and screw plug, wherein the screw element may be efficiently locked in a retracted position within the skirt casing, while the device is being used as a prong plug.

Other objects and advantages of this invention will appear throughout the following specification and claims.

In the drawing:

Figure 1 is a side elevational view of the plug with the screw element in an extended position, the lower threaded cap being shown in section;

Figure 2 is a central vertical sectional view taken on a line with the ring-engaging bayonet slots formed in the skirt casing;

Figure 3 is a side elevational view of the screw element, certain parts being shown in section;

Figure 4 is a perspective view of the insulated core element, one of the contact elements being removed;

Figure 5 is an enlarged top plan view of the core element, both contact elements being shown in position;

Figure 6 is a fragmentary vertical sectional view taken on a line with the slots which receive the anchoring pins, a part of the core element being shown in section, and a part of the screw element being broken away;

Figure 7 is a perspective view of the screw element-actuating ring which carries the screw element;

Figure 8 is a fragmentary perspective view of the ring shown in Figure 7;

Figure 9 is a perspective view of the skirt shell, illustrating the relative locations of the bayonet slots and the slots which receive the anchoring pins.

By referring to the drawing, it will be seen that 10 designates the skirt casing which is provided with a depending externally threaded portion 11 for detachably receiving the internally threaded cap 12. The depending threaded portion 11 constitutes a base to which the inner ends 13 and 14 of the prongs 15 and 16 are secured in the manner shown in Figure 2. These prongs extend through suitable apertures formed in the portion 11, the apertures being slightly

2

larger than the prongs to facilitate placing of the prongs in position and also to permit the prongs to slightly flex when necessary. The lead wires 17 and 18 are connected to the prongs 15 and 16 by means of suitable screws 19 and 20.

The skirt casing 10 is provided with longitudinally diametrically opposite bayonet slots 21 which extend through the upper or outer end 23 of the casing 10, as shown in detail in Figure 9. The respective slots 21 are provided with oppositely extending lateral portions 24 at their inner ends for the purpose described in the following. A pair of anchoring pin-receiving slots 25 extend longitudinally of the casing 10 intermediate the bayonet slots 21 and the slots 25 are preferably arranged in diametrically opposite relation to each other. The slots 25 terminate short of the outer end 23 of the casing 10 and are closed at their outer ends, as shown.

20 A screw element-actuating ring 26 is slidably mounted upon the casing 10. This ring 26 comprises an outer band 27 and an inner band 28. These bands 27 and 28 are held in relative spaced relation by means of a pair of diametrically opposite integral lugs 29. The band 28 is adapted to fit snugly against the inner face of the casing 10, and the band 27 is adapted to fit snugly around the outer face of the casing 10. The integral lugs 29 pass through the slots 21 and permit the ring 26 to slide longitudinally of the casing 10.

25 The ring 26 carries a protruding threaded metal shell 30 which is provided with a depending inset rim or skirt 31 defining a shoulder 32. The rim or skirt 31 is fixed to the inner face of the band 28 and the shoulder 32 is fixed to and overhangs the outer face of the band 28. The shell 30 and the ring 26 therefore constitute one unitary element, the shell 30 being formed of conducting metal, and the ring 26 being formed of insulating material.

30 A core element 33 formed of insulating material is carried within the shell 30 and is fixed against rotary movement within the shell 30 by means of anchoring pins 34 which pass through the slots 25 of the casing 10 and are threaded or otherwise secured in the lower end of the core element 33, as shown in Figure 6. One or more of these pins 34 may be used without departing from the spirit of the invention. The pins 34 extend transversely through the slots 21 and into the core element 33 and abut the outer closed ends of the slots 25 to limit the outward movement of the core element 33 relative to the outer 35 end 23 of the casing 10. The core element 33

carries a conducting band of metal 35 which overhangs the shoulder 32 of the shell 30. The band 35 is fixed to the insulating core element 33 and the band 35 holds the core element 33 against independent longitudinal movement in one direction, while the pin or pins 34 which abut the under face of the ring 26 hold this core element against independent longitudinal movement in the opposite direction relative to the ring 26. The ring 26 which therefore carries the shell 30 and core member 33 may be moved longitudinally of the casing 10 as one element, from a retracted to an extended position to a point where the lugs 29 of the ring 26 overlie the outer ends of the slots 21. The ring 26 to which the threaded shell 30 is fixed may be freely rotated, the lugs 29 moving circumferentially of the outer end 23 of the casing 10, and the bands 27 and 28 rotating freely around the casing 10. In this manner, the shell 30 may be easily threaded into a threaded or screw socket without rotating the casing 10.

When the ring 26 is moved inwardly of the outer end 23 of the casing 10, the lugs 29 will slide longitudinally of the slots 21, and by slightly turning the ring 26 the lugs 29 may be fastened within the lateral portions 24 of the bayonet slots 21 and thereby removably secure the screw element, comprising the ring 26, the shell 30, and core member 33 in a shielded and retracted position within the casing 10, as shown in Figure 2.

The core member 33 is provided with a longitudinal aperture 36 through which the prong 15 extends, and a longitudinal aperture 37 through which the prong 16 extends. The band 35 is provided with a contact strip 38. This strip 38 is provided with an inturned contact finger 39 which extends downwardly through the outer end of the aperture 36 of the core member 33, to provide a slidable spring contact with the prong 15, which extends through the aperture 36.

A central contact plate 40 is countersunk in the socket 41 formed in the outer end of the core member 33, and is anchored in position by means of the central contact pin or screw 42 of the conventional type, which screw 42 also retains the covering insulating disc 43 of the conventional type in place. The disc 43 is suitably apertured to permit the prongs 15 and 16 to extend therethrough. The plate 40 is cut out, as at 44, and a spring-bowed contact finger is bent downwardly therefrom to extend down into the upper or outer end of the aperture 37 of the core element 33 for contact with the prong 16 when the screw element comprising the ring 26 and shell 30, is extended to the position shown in Figure 1. The prong 16 is provided with an offset portion 46 and the outer end of the slot 37 is restricted, as at 47, just beyond the bowed portion of the finger 45 to cause the bowed portion of the finger 45 to break contact with the offset portion 46 when the screw element is in a retracted position. This will break the circuit through the shell 30. As the screw element is moved outwardly of the casing 10 the finger 45 will close the circuit through the prong 16.

As shown in Figure 2, the outer ends of the prongs 15 and 16 preferably are apertured, as at 48. When the screw element is extended to the position shown in Figure 1, the outer ends of the prongs 15 and 16 are shielded within the apertures 36 and 37 of the core element 33. The ring 26 and the shell 30, however, may be freely rotated for threading the shell 30 into a screw socket. The current will then pass through the

pin 42 from the receptacle or socket to the plate 40, the finger 45, the prong 16, to the outlet wires 17 and 18, and back through the prong 15, the finger 39, the strip 38, the band 35, and the shell 30 to the receptacle or socket in which the plug is secured.

When the screw element is retracted to the position shown in Figure 2, the prongs 15 and 16 will protrude beyond the screw element and may fit into a prong-receiving receptacle. The current will then pass through prong 16, and back through prong 15, the shell 30 being dead.

From the foregoing description, it will be seen that a very simple and efficient plug has been produced which may be adjusted for use either as a screw plug or a prong plug.

Having described the invention, what is claimed is:

1. A plug of the class described comprising a hollow casing, current-conducting prongs carried by and extending longitudinally of the casing, a screw element movable to a retracted and to an extended position relative to said casing and comprising an actuating ring, a threaded shell fixed to said ring, an insulated core member carried by the ring and fixed against longitudinal movement relative to the ring, the ring and shell being rotatable relative to the core member, means for locking the ring against rotation relative to the casing when the screw element is retracted and releasing the ring for rotation when the screw element is extended to facilitate the threading of the shell into a threaded socket, said screw element being movable to a position beyond the prongs when the screw element is in an extended position, the prongs extending beyond the screw element when the screw element is in a retracted position, a contact terminal carried by the core member, means carried by the core member for electrically connecting one of the prongs to the shell, and means for connecting the other prong to the contact terminal of the core member.

2. A plug of the class described comprising a hollow casing, current-conducting prongs carried by and extending longitudinally of the casing, a screw element movable to a retracted and to an extended position relative to said casing and comprising an actuating ring, a threaded shell fixed to said ring, an insulated core member carried by the ring and fixed against longitudinal movement relative to the ring, the ring and shell being rotatable relative to the core member, means for locking the ring against rotation relative to the casing when the screw element is retracted and releasing the ring for rotation when the screw element is extended to facilitate the threading of the shell into a threaded socket, said screw element being movable to a position beyond the prongs when the screw element is in an extended position, the prongs extending beyond the screw element when the screw element is in a retracted position, a contact terminal carried by the core member, means carried by the core member for electrically connecting one of the prongs to the shell, means for connecting the other prong to the contact terminal of the core member, and means for breaking the circuit between the last-mentioned prong and said contact terminal when the screw element is retracted.

3. A plug of the class described comprising a hollow casing, current-conducting prongs carried by and extending longitudinally of the casing, a screw element movable to a retracted and

to an extended position relative to said casing and comprising an actuating ring, a threaded shell fixed to said ring, an insulated core member carried by the ring and fixed against longitudinal movement relative to the ring, the ring and shell being rotatable relative to the core member, means for locking the ring against rotation relative to the casing when the screw element is retracted and releasing the ring for rotation when the screw element is extended to facilitate the threading of the shell into a threaded socket, said screw element being movable to a position beyond the prongs when the screw element is in an extended position, the prongs extending beyond the screw element when the screw element is in a retracted position, a contact terminal carried by the core member, means carried by the core member for electrically connecting one of the prongs to the shell, means for connecting the other prong to the contact terminal of the core member, and means for breaking the circuit between the screw element and one of the prongs when the screw element is retracted.

4. A plug of the class described comprising a casing, current-conducting prongs carried by and having protruding ends extending beyond said casing, a screw element movable to a retracted and to an extended position relative to said casing and comprising an insulated actuating ring, a conducting threaded shell fixed to said ring and constituting one contact terminal, an insulated core member carried by said ring and fixed against longitudinal movement relative to said ring; the ring and shell being rotatable relative to the core member, said screw element being movable to a position beyond the prongs when the screw element is in an extended position, the prongs extending beyond the screw element when the screw element is in a retracted position, a second contact terminal carried by the core member, means electrically connecting one of the prongs to the shell, means electrically connecting the other prong to said second contact terminal, said casing having a longitudinally extending guiding slot, said ring comprising a pair of spaced insulated bands, one band fitting within said casing, the other band fitting around the exterior of said casing, band connecting means normally extending through said guiding slot and connecting said bands to hold the ring against rotation relative to said casing, and the slot being open at the outer end of the casing to facilitate the moving of the band connecting means beyond said casing and to facilitate the rotation of the ring relative to the casing to thread the shell into a screw socket.

5. A plug of the class described comprising a casing, current-conducting prongs carried by and having protruding ends extending beyond said casing, a screw element movable to a retracted and to an extended position relative to said casing and comprising an insulated actuating ring, a conducting threaded shell fixed to said ring and constituting one contact terminal, an insulated core member carried by said ring and fixed against longitudinal movement relative to said ring; the ring and shell being rotatable relative to the core member, said screw element being movable to a position beyond the prongs when the screw element is in an extended position, the prongs extending beyond the screw element when the screw element is in a retracted position, a

second contact terminal carried by the core member, means electrically connecting one of the prongs to the shell, means electrically connecting the other prong to said second contact terminal, said casing having a longitudinally extending guiding slot, said ring comprising a pair of spaced insulated bands, one band fitting within said casing, the other band fitting around the exterior of said casing, a lug normally extending through said guiding slot and connecting said bands to hold the ring against rotation relative to said casing, the slot being open at the outer end of the casing to facilitate the moving of the lug beyond said casing and to facilitate the rotation of the ring relative to the casing to thread the shell into a screw socket, and said slot having a lateral socket at its inner end for receiving said lug when the screw element is retracted into said casing to hold the screw element in a retracted position.

6. A plug of the class described comprising a casing, current-conducting prongs carried by and having protruding ends extending beyond said casing, a screw element movable to a retracted and to an extended position relative to said casing and comprising an insulated actuating ring, a conducting threaded shell fixed to said ring and constituting one contact terminal, an insulated core member carried by said ring and fixed against longitudinal movement relative to said ring; the ring and shell being rotatable relative to the core member, said screw element being movable to a position beyond the prongs when the screw element is in an extended position, the prongs extending beyond the screw element when the screw element is in a retracted position, a second contact terminal carried by the core member, means electrically connecting one of the prongs to the shell, means electrically connecting the other prong to said second contact terminal, said casing having a longitudinally extending guiding slot, said ring comprising a pair of spaced insulated bands, one band fitting within said casing, the other band fitting around the exterior of said casing, band connecting means normally extending through said guiding slot and connecting said bands to hold the ring against rotation relative to said casing, the slot being open at the outer end of the casing to facilitate the moving of the band connecting means beyond said casing and to facilitate the rotation of the ring relative to the casing to thread the shell into a screw socket, and means slidably connecting the core and casing and limiting the sliding movement of the core relative to the casing to prevent accidental displacement of the core relative to the casing when the screw element is moved to an extended position.
